SINGLE THREAD LOCKING STITCH

Filed Aug. 13, 1951

FIG. 5.

1

2,696,795

SINGLE THREAD LOCKING STITCH

Louis Kirsch, New York, N. Y.

Application August 13, 1951, Serial No. 241,527

3 Claims. (Cl. 112—262)

The present invention relates to a lock stitch which is formed from a single thread.

Lock stitches have heretofore been proposed but such stitches have been interlinked with each other to prevent them from unraveling or being pulled apart. To sew such lock stitches of the prior art, the sewing machines used for forming them have included bobbins or spools containing the lower thread.

The present invention therefore contemplates the provision of a lock stitch that is formed from only a single thread which single thread is so intertwined or interlinked in the stitching that application of tension at any loose or severed portion of the thread will cause an adjacent stitch to lock so that the thread can not unravel and be pulled out from the material to which it has been sewed.

The present invention contemplates the provision of a stitch construction such that each stitch is individually locked so that should the thread break at any point, it cannot be pulled out or the material which has been sewn together by it, separated, thereby providing a lock stitch that is superior to those heretofore proposed.

Heretofore, bobbin made stitches have been used to sew seams together but should the thread thereof break, the seam will open, since each stitch thereof is not individually locked. In distinction, should the thread break in a stitch of the present invention which has been applied to sew together a seam, it (the seam) will not open since the stitches are individually locked.

Since the present invention contemplates the provision of a lock stitch formed from a single thread, the sewing machine that is used will have no bobbin and may therefore be used with a relatively heavy thread of any size, which heretofore has not been possible since machines employing bobbins must be limited to relatively light threads.

By the provision of the single thread lock stitch of the present invention, where otherwise it would be desired to use a lock stitch of the prior art employing at least two threads, there is eliminated in machines which have many needles, the requirement of an equal number (for the additional thread) of tension devices and bobbins, spools of yarn, etc., thereby reducing the size and complexity of the apparatus required.

In the past, sewing machines which require a bobbin generally when used with heavy threads, are extremely large, of comparatively great weight and are limited in the size of thread since the size of the bobbins are limited. However, since with the single thread lock stitch of the present invention, bobbins, bobbin winders, spools of yarn and tensioners, are eliminated from the sewing apparatus, it is comparatively small and of light weight.

These bobbin machines require frequent replenishing of the bobbins thereby increasing the cost of labor and causing such sewing machine to be repeatedly idle. On the other hand, the sewing machine forming the lock stitch of the present invention eliminates these disadvantages of bobbin machines and yet provides a mechanically superior stitch reducing most considerably the set-up time and bobbin replenishing time and results in a machine which comparatively is not idle.

In these bobbin machines, which are continuously operated, requiring replacement of the bobbins, breaks in the stitch will occur requiring repair to the slipped or skipped stitches. Such repair is also required when a

2

machine is stopped for the replacement of an empty bobbin. On the other hand, with sewing machines forming the lock stitch of the present invention, such repair to the stitches is unnecessary and the flow of work sewed thereby will be continuous.

The present invention further may be applied to an existing chain stitch machine to convert it into one by which a lock stitch may be sewed without the addition of bobbins or extra threads for each needle of the machine.

My invention also will have great application to shirring machines which have a multiplicity of needles since it makes unnecessary the requirement of a large quantity of additional spools of thread and tensioners to lock the stitch, thereby increasing the quantity of work, rate of production and reduction in required size of multiple needle shirring machine equipment.

These, other and further objects, advantages and uses of the present invention will be clear from the description which follows and the drawings appended thereto, in which

Fig. 1 is a plan view of a lock stitch formed from a single thread according to my invention.

Fig. 2 is a section on the line 2—2 of Fig. 1, showing the stitch locked in both directions.

Fig. 3 is a similar sectional view with the stitch opened to show its construction.

Fig. 4 is a bottom plan view of Fig. 1.

Fig. 5 is a section on the line 5—5 of Fig. 2.

Fig. 6 is a section on the line 6—6 of Fig. 2.

Referring now to Figs. 1 to 6 inclusive, I have illustrated a lock stitch embodying my invention which is formed from the single thread 10 and by which the fabrics 12 and 14 are sewed together.

In the description herein, a complete stitch as viewed above the upper textile or fabric 12, shall be considered as formed by the thread between the point 16 at which it enters the upper textile or fabric 12 to form the first stitch 18 and the point 20 at which it enters the upper textile or fabric 12 to form the succeeding stitch 22.

As viewed below the under textile or fabric 14, a complete stitch shall be considered as formed by the thread 10 between the loop 24 of the preceding stitch 26 at the point of entry 16 and the loop 28 of the first stitch 18 at the point of entry 20 to form the succeeding stitch 22.

As will be more fully described on the underside of the textiles or fabrics which are sewn together by my single thread lock stitch, the thread 10 is formed into the integral knot 30 which is located between the loop 24 of the preceding stitch 26 and the loop 28 of the first stitch 18.

Thus, every lock stitch according to my invention includes on the underside of the textile fabric, where it is not ordinarily visible, a knot, by means of which the stitches are individually locked, and, as will be seen, prevented from unraveling. The lock stitches appear above the textile or fabric, similar to a standard stitch.

For an understanding of my description, it shall be understood that the portion of the thread which goes through the loop of a preceding stitch is to the left of the figures (Figs. 1 to 4) and the portion of the thread that continues into the succeeding stitch through the loop of the stitch itself is on the right of these figures.

The needle of the sewing machine (not shown) by means of which my novel lock stitch may be sewed, pierces the textile or fabrics 12 and 14 and carries the yarn or thread 10 with it, through the loop of the preceding stitch to underneath the textile or fabric.

It (the yarn or thread 10) through the operation of a sewing mechanism, which is described and claimed in my co-pending application, then continues into the coil or node 34 (see Fig. 3) of the knot 30 (see Fig. 2) to pass into and form the loop 28 of the stitch 18.

From there, the yarn or thread 10 returns to complete the formation of the coil or node 34 continuing back and then drawn by the needle of the sewing machine through the loop 24 of the preceding stitch 26 to above the textile or fabric.

The material is fed by the feed dog and the needle.

again enters the textile or fabric at the second point of entry 20 to complete the stitch 18 thereabove and through the loop 28 of this stitch 18 to commence formation of the succeeding stitch 22.

The operations are continued to form the succeeding knot 36 (see Fig. 2) its coil or node 38 (see Fig. 3) and its loop 40 in the manner just described.

It will now be apparent that by means of the knot formed on the underside of the sewn fabrics, the stitch is locked in both directions, as is illustrated with particularity in Fig. 2.

With the lock stitch here proposed, referring to Fig. 2, should the thread of the stitch above the textile or fabric be broken and tension applied to that portion 42 of the thread located to the left of and leading to the loop 28, as indicated by the arrow 31, then the loop 28 will be tightened around the thread 35 going to the succeeding stitch 22. This tightening of the loop locks the stitch at that point.

Should tension be applied in the direction of the arrow 48 to the portion 44 of the thread or yarn, leading to a knot, which for convenience in illustration and description, I refer to by the reference numeral 46 (see Fig. 2), upon breaking the thread forming the stitch above the textile or fabric, then this knot 46 will be tightened and the stitch will be locked there because the knot cannot be drawn through the loop 50. This loop 50, it will be recognized, is similar or analogous to the loop 24.

It will be noted from the figures that all of the loops, such as 24, 28, 40, 50, are small to prevent knots, such as 30, 36, 46, from being drawn therethrough in the event of breakage of the thread which would otherwise occur if such loops were large enough to permit the knots to be drawn therethrough. This feature is best seen in Figure 2 where it is quite apparent that knot 46, for example, could not be drawn through the bight of loop 50. In other words, the loops are close to the knots and do not extend outwardly therefrom to permit these loops to open sufficiently to pass a knot in the event of breakage of a thread. It will also be noted that should a thread break releasing loop L1 (Figure 2) and tension be applied to the free top strand 44 as indicated by arrow 48 (Figure 2), the knot 46 of the broken stitch will be drawn toward loop 50. This causes a slackening and doubling of lower strand S which, together with knot 46, is too bulky to pass through loop 50.

Thus, if the stitch breaks above the fabric or textile, it cannot slip and be unraveled but will be locked at this point.

An inspection of Fig. 4 establishes that the thread or yarn leads to a knot 30 and therefore should the thread or yarn break beneath the lower textile or fabric 14, any tension applied to a loose end will result only in tightening the knot to which it leads.

Thus, the effect below the fabric is the same as that above the fabric, that is, the stitch cannot slip and unravel but will lock at the point at which the yarn or thread might break.

It will now be apparent that I have provided a lock stitch formed from a single thread that cannot unravel or be pulled out of the textiles or fabrics which are sewn together by it and thereby separated should the thread break at any part thereof.

It will be further recognized that I have proposed in each stitch between the loop thereof and the loop of the preceding stitch the provision of an integral knot formed in the thread comprising the stitch and which knot individually locks the stitch when tension is applied or transmitted to the knot or loop by pulling the fabric apart or pulling the free end of the thread. Thus, there is now provided a lock stitch sewed from a single thread which eliminates the necessity of another thread and corresponding requirement of a bobbin, bobbin winder, second spool of yarn and tensioner.

While I have shown and described a certain specific example of my invention, it will be understood that such example is illustrative only and is not given as a limitation, since other modifications within the spirit and scope of the invention will be apparent to those skilled in the art.

It will also be understood that the lock stitch suggested herein and having an integral intermediate knot continuing from spaced loops on each side of the knot, the loops and the knot being formed from the same thread, may have other applications, for example, in the art of knitting.

Hence, I do not intend to limit myself thereto, but intend to claim my invention as broadly as may be permitted by the state of the prior art and the terms of the appended claims.

I claim:

1. A single thread locking stitch comprising a line of lengths of single thread on the top side of the material to be sewn, and a series of in-line loops interlocked with succeeding loops on the underside of said material, each loop having a knot adjacent its bight end portion whereby each said knot is prevented from passing through said bight portion of each preceding loop.

2. The locking stitch as defined in and by claim 1, wherein the dimensions of the openings formed by the bight portions of the loops relative to the size of the knots are such as to prevent the knots from passing through the said openings.

3. The locking stitch as defined in and by claim 2, wherein said thread has a free end when broken and when said end is pulled, the first knot thereon engages the bight portion of a preceding loop, the thread adjacent the knot being drawn backward to produce a doubling effect and which jointly with said knot assists in locking the stitches.
